UNITED STATES PATENT OFFICE.

FRANK M. VOGAN, OF CANTON, OHIO.

MOLD FOR CONCRETE CONSTRUCTION.

1,224,584.

Specification of Letters Patent. Patented May 1, 1917.

Application filed May 1, 1915. Serial No. 25,280.

To all whom it may concern:

Be it known that I, FRANK M. VOGAN, a citizen of the United States, residing at Canton, in the county of Stark and State 5 of Ohio, have invented a new and useful Mold for Concrete Construction, of which the following is a specification.

My invention relates to improvements in molds for concrete construction to be used 10 for forming concrete structures such as buildings wherein the walls, floors and ceilings are cast in plastic concrete and when hardened produce substantially a monolithic structure.

15 More especially the present invention relates to a mold of this character which is made up of separable units, each of said units being provided with a molding face which may be of any ornamental design.

20 The object of the invention is to provide knock-down forms or surface molding units, preferably made of sheet metal and adapted to be connected in any appropriate relative position to produce different desired surface 25 effects and to accommodate rooms of various sizes and proportions.

A further object is to provide surface 30 molding units which are composed of comparatively heavy material and provided with detachable molding faces which are formed of comparatively light material.

Another object is to provide means whereby various surface molding units may be altered so as to produce various detailed 35 ornamentation of the finished surface, or to produce more or less detailed ornamentation, as may be desired.

With these objects in view the invention 40 consists in the novel construction and arrangement of parts, hereinafter described, illustrated in the accompanying drawings, and particularly pointed out in the appended claims, it being understood that various changes in the form, proportions, 45 size and minor details of construction may be made within the scope of the appended claims, without departing from the spirit or sacrificing any of the advantages of the invention.

50 In the drawings:

Figure 1 is a view principally in perspective and partly in section, illustrating mold units assembled and arranged for the construction of a ceiling with pendant decoration member and pillars, showing the false

work units which support the same, a portion of the mold units and false work being broken away to more fully disclose the details.

Fig. 2 is an underside perspective view 60 of a recessing mold unit provided with appliquéd removable detailed decoration plates.

Fig. 3 is a top side perspective view of a similar mold unit provided with a movable pendant center decoration member, the pendant 65 decoration member and one of the appliquéd decoration plates being removed.

Fig. 4 is a perspective view of the pendant 70 decoration member removed from the mold unit illustrated in Fig. 6.

Fig. 5 is a perspective view of the appliquéd decoration plate removed from the mold unit illustrated in Fig. 6.

Fig. 6 is an enlarged fragmentary vertical sectional view through a mold unit 75 such as illustrated in Fig. 6, the pendant decoration and the appliquéd decoration plate being attached.

Fig. 7 is a perspective view illustrating mold units assembled and arranged for the 80 construction of a pillar, portions being broken away to more fully disclose the details.

Fig. 8 is a fragmentary perspective view 85 upon an enlarged scale of a portion of one of the mold units shown in Fig. 7.

Fig. 9 is a horizontal sectional view on the line 13—13, Fig. 7.

Fig. 10 is a fragmentary sectional view 90 showing the means for connecting the appliquéd sheets to the mold units.

Similar numerals of reference indicate corresponding parts throughout the several views of the drawings.

In a preliminary and general way it may 95 be stated that my invention contemplates sheet metal mold units embossed with the design which it is desired to impart to the surface of the concrete wall, ceiling, pillar, or other structure to be cast, or provided with appliquéd plates or sheets embossed with the proper design, the marginal edges of each mold unit being bent outwardly away from said surface to afford means for holding said unit in position upon the supporting false work. Said mold units are preferably made in predetermined standard sizes adapted to fit together in various combinations and said false work is also made up of standardized units provided with 100 105 110

means for receiving and holding the said outturned marginal edges of the mold units. Although the present invention has more especial relation to the construction and operation of the mold units, it is necessary that some form of false work be employed to support the mold units in assembled relation and although any suitable form of false work may be provided for assembling the sections the preferred form of false work is illustrated in the accompanying drawings and before a further and more specific description of the mold units is given the false work such as is illustrated will be described in a general way.

Each false stringer unit comprises a stringer base 1 which is preferably made of wood of a sufficient size to withstand the weight and strains to which it will be subjected as hereinafter more fully disclosed. Connected to the stringer base 1 is the vertically extending stringer web 2 preferably formed of two juxtaposed timbers set up upon one edge. Extending along the upper free edge of the web 2 is a compound slot comprising the shallower, broader joint-bead forming portion 3 and the mold margin-receiving portion 4 extending from the bottom of the portion 3 deeper into the web and being narrower than the portion 3 so as to produce oppositely disposed off-sets or shoulders 5. In order to provide against rapid wear the slot is preferably provided with a sheet metal lining 6, the edges 7 of said lining being countersunk into the edge of the web 2.

At predetermined equal intervals of spacing along the web 2 are transverse mold joint notches corresponding in cross sectional shape to the cross sectional shape of the longitudinally disposed slot just described and on both sides of the web 2 adjacent said notches are pairs of joist holding blocks 9 provided on their under edges with upwardly rounded longitudinally disposed grooves. The said blocks 9 are for the purpose which will hereinafter more fully appear.

Referring now to the joist units it will be noted that each is formed of the joist web 11 provided along its upper edge with a compound slot of the same cross sectional shape and size as the slot in the stringer web just above described. The parts of the slot in the joist units illustrated are numbered the same as the parts of the slots of the stringer units. The joist base is preferably not formed in the same manner as the stringer base, but is formed by two joist base-strips 12 fixedly connected to the lower side edges of the webs 11. The joist web at both ends of the joist unit extends slightly beyond the ends of the joist base. At each end of the joist is also arranged a transverse spline member 13 provided with a rounded

upper edge adapted to fit into the upwardly curved grooves in the blocks 9 above described. The upper edge of each spline member 13, it will be understood, is above the upper surface of the joist base-strips 12. It should be stated at this point that the two blocks 9 of each pair are spaced from each other just the necessary distance to receive between them the web 11 of the joist unit and the upper edge of the spline member 13 with relation to the upper edge of the web 11 is such that when the upper edge of said web 11 is raised to coincide with the upper edge of the web 2 of one of the stringers the said spline 13 will engage the grooves in the blocks 9. The height of the webs 11 is less than the height of the webs 2 so that a joist unit may be arranged with its base on top of the base 1, the web 11 extending at right-angles to the web 2 and the end of the joist unit may then be moved along upon the base 1 until the proper relative position with the blocks 9 has been reached, whereupon the joist unit may be raised until the said spline 13 engages the grooves in the blocks 9, and a joist supporting block 14 may then be arranged between the underside of the base of the joist unit and the top side of the base 1 of the stringer unit to support said joist unit and hold it in firm engagement with the stringer unit. When in this position it will be understood that the compound slot of the joist unit registers with the mold joint notch in the stringer unit.

It will be understood that in setting up false-work in accordance with my invention a plurality of stringer units will be placed in parallel and equally spaced arrangement and a plurality of joist units will then be employed to connect the various stringer units, said joist units extending transversely with reference to said stringer units.

In the construction of ceilings it will usually be found desirable to provide sheet metal mold units which, throughout their greater extent, will require support in order to sustain the great weight of the plastic concrete cast upon them. It will hereinafter more fully appear that the edges of such mold units will be sufficiently supported by the stringers and joists.

In setting up the false-work for the construction of the walls and ceiling of a room a heavy supporting frame must be provided, the cross beams 21 of which are adapted to receive and support the false stringer units which extend transversely with relation to said beams. The beams 21 extend substantially to the side walls of the room and at the side walls are the beam supporting and wall framing vertical units. Said vertical units are substantially the same in construction as the stringer units.

As an illustration of one type of ceiling which it is convenient to construct in ac-

cordance with my invention attention is called to Fig. 1. Therein it will be noted that the field of said ceiling is formed of a plurality of square panels 23, the outer 5 row of panels around the room being provided with egg and dart decorative molding and the central portion of each panel being depressed. In Fig. 1 the panel inside of the outer row is shown without the decorative 10 molding and it will be understood that such panels may be formed in such plain fashion or decorated as may be desired. Between the panels extends a portion 24 in high relief which may be termed the frame portion 15 and which not only extends between the various panels, but also externally with relation to the outer panels. A pendant decoration member 27 is shown in the center of the panel 23 and it will be understood that 20 these pendant decorations may be provided at intervals upon the ceiling for the purpose of decoration or in order to accommodate chandeliers or lamp globes.

Referring now to the mold units, it will 25 be understood that the same are stamped from sheet metal and an inspection of Fig. 2 will give an understanding of the form of said units designed for the molding of the various panels forming the field of the ceiling, such as illustrated in the outer row of 30 panels in Fig. 1. Each panel unit of this kind is formed exactly square and is provided with a joint-bead-forming compound flange 33, illustrated in a number of the figures of the drawings, and with a marginal holding flange 34. Two opposite edges of 35 said panel mold unit are let into the slots of adjacent stringers and the other two opposite edges are let into the slots of adjacent 40 joist units. If desired the compound flanges 33 fitting into the joint-bead-forming portions 3 of the slots may be left open to form a joint-bead in high relief in the molded surface, or a joint fillet 35 comprising a strip 45 of material may be arranged as illustrated in Fig. 1 to fill the said space and prevent the molding of such a joint-bead.

After the ceiling and wall mold units have 50 been properly arranged and connected as described and illustrated the plastic concrete is poured from above between the wall mold units and on top of the ceiling mold units and permitted to harden. When the concrete has sufficiently set and hardened the 55 false-work units as well as the mold units may be removed section by section and again used at other places in the same or different combinations.

It will be understood that in carrying out 60 my invention the concrete first applied to the mold unit surfaces should be of finer quality than is necessary for the internal or body portions of the structure. This is for the purpose of producing a finer and more elegant surface in the finished wall or ceiling

and for the purpose of more faithfully reproducing every detail of decoration embossed in the mold units.

As for instance in the field-panel mold units such as illustrated in Fig. 2, it is some 70 times desirable to change the detail decoration, as from the egg and dart pattern to that of some other pattern of molding. In order to provide not only for the convenient and ready change of decoration without requiring the entire mold unit to be changed or replaced, but to provide for the making of the ornamental portions of the mold units from sufficiently thin material to properly draw under the drop hammers or presses 75 so as to produce sharp and distinct and even and perfect lines and also for the purpose of the ready removal of the deeply stamped decorative portions of the molds from the finished molded surface, I provide appliquéd 80 decoration members 38 stamped from comparatively thin material and adapted to be applied to the heavier mold units 39. In Fig. 3 is shown a mold unit from which one 85 of the appliquéd molding members has been removed. Said member is shown in Fig. 5 and will be seen to comprise merely a strip 90 of material embossed with the decoration desired and provided with apertures 49 adapted to register with apertures 50 in the mold 95 unit to provide for fastening means, such as bolts or rivets to fasten the appliquéd members to the mold unit. Without the appliquéd members such a mold unit would produce a panel such as the plain or undecorated panel 100 illustrated in the upper right hand corner of Fig. 1. With the appliquéd members connected to the mold section however the egg and dart decoration illustrated in the other panels will be produced. The pendant decoration member 51 which is illustrated in Fig. 105 4 is provided around its upper edge with an outwardly disposed annular flange 52 adapted to rest upon the annular shoulder 53, which is provided around the periphery of 110 the aperture 54 in the field mold unit shown in Fig. 3, the apertures 55 provided in the flange 52 being arranged to register with the apertures 56 upon the annular shoulder 53 for the purpose of receiving bolts or other 115 means of temporarily attaching said members together. It will be understood that any other suitable ornamentation may be substituted for the pendant member 51. In removing the mold sections from the finished 120 concrete surface, where the decoration involves deep indentations or high projections it may be desirable to disconnect the appliquéd members from the mold sections before removing the mold section itself. Then 125 the mold section may be removed and the appliquéd members removed one by one, said members being sufficiently thin to be bent and warped to remove them from the decorated surface without injury thereto. 130

1 In Fig. 7 is illustrated the method of forming a concrete pillar with the use of a combination of mold units provided with appliquéd members, said appliquéd members being formed of lighter material than the mold sections and embossed with the designs desired to be conveyed to the finished concrete structure. The mold used in forming the pillar illustrated in Fig. 7, comprises the upper mold units which form the upper portion A of the shaft and the capital B and the lower mold units which form the lower portion C of the shaft and the base D. The lower mold units designated by the numeral 15 58 each comprise a heavy rectangular sheet of metal, the lower portion of said sheet being shaped to conform substantially with the design desired to be applied to the base of the pillar. Each of said sheets is provided along each of its vertical edges with an outstanding angular flange 59 and with out-turned horizontal flanges 60 and 61 along the top and bottom edges thereof respectively. An appliquéd decoration sheet 62 is 20 temporarily attached upon the inner face of each of said mold units, each of said appliquéd decoration sheets being provided with side flanges 63 and upper and lower horizontal flanges 64 and 65 respectively, said 25 appliquéd sheet having embossed thereon the design desired to be applied to the pillar, the appliquéd decoration sheets illustrated in the accompanying drawings being provided with a series of vertical ribs 66, adapted to 30 imprint corresponding impressions in the face of the pillar and with any suitable design which may be desired upon the base. Each of the upper mold units is formed substantially the same as the lower mold units, 35 each upper unit being provided along its vertical edges with outstanding angular flanges 67, said upper mold units being also provided with upper and lower horizontal flanges, the appliquéd decoration plates adapted to be connected to said upper mold units 40 being formed in substantially the same manner as the appliquéd decoration plates attached to the lower mold units. When it is desired to build up a mold for forming a 45 pillar or similar structure the appliquéd decoration sheets are placed upon the inner faces of the mold units and bolts or their equivalents 68 are passed through suitable apertures in the flanges 59 and 63, thus holding 50 each tier of mold units and appliquéd decoration sheets rigidly together. The upper and lower tiers of mold units are connected to each other by means of the horizontal flanges upon the bottom of the upper mold 55 units and the top of the lower mold units 60 respectively, bolts being passed through suitable apertures formed in these flanges. The vertical flanges of the mold units and appliquéd decoration sheets are each notched at 65 intervals as at 69 to receive the tie bands

70. Blocks 71 provided with centrally located vertical ribs 72 are interposed between the mold units and the tie bands, said tie bands being tightened by means of bolts 73 holding the blocks rigidly against the mold units and preventing any warping or bulging of the mold units when the liquid cement is poured into the mold. For economical reasons a core 74 may be placed within the center of the pillar as best shown in Fig. 9 thus forming a hollow pillar. In Fig. 8 is shown a portion of a mold unit and appliquéd decoration sheet for forming the base of a pillar slightly different in design from the base shown in Fig. 7, the general construction of this mold unit being substantially the same as that shown in Fig. 7. The mold units are shown provided with ribs 75 and concavities 76 through which screws 77 are passed, said screws engaging internally screw threaded lugs 78 which are formed at intervals upon the appliquéd decoration sheets 79. A detail of one of these connections is illustrated in Fig. 10 of the drawings. 90

Although the drawings and above specifications disclose the best mode in which I have contemplated embodying my invention I desire to be not limited to the details of such disclosure, for, in the further practical application of my invention, many changes in form and construction may be made, as circumstances require or experience suggests, without departing from the spirit of the invention, within the scope of the appended claims. 95

I claim:

1. For concrete construction a sheet metal mold unit of relatively thick material and an appliquéd decorative member stamped from comparatively thin material and adapted to be removably connected to said mold unit. 105

2. For concrete construction a sheet metal mold unit provided with an aperture having a marginal edge provided with an off-set and an auxiliary mold member arranged in said aperture and having its marginal edge located in said off-set. 110

3. For concrete construction a sheet metal mold unit and an appliquéd decorative member, flanges located around the edges of said mold unit and said appliquéd decorative member, said flanges provided with apertures and bolts located through the apertures for removably connecting the said appliquéd decorative member to said mold unit. 115 120

4. For concrete construction a sheet metal mold unit and an appliquéd decorative member stamped from comparatively thin metal and adapted to be removably connected to said mold member, depressions formed in said mold unit, said depressions provided with apertures, projections formed upon said appliquéd decorative member and adapted to 125 130

- register with the depressions in the mold unit, said projections provided with screw threaded apertures and screws located through the apertures in said mold units 5 and through the screw threaded apertures in the projections.
5. For concrete construction a sheet metal mold adapted to form a pillar or the like comprising a plurality of sheet metal mold units, a plurality of appliquéd decorative members stamped from comparatively thin material and provided with flanges at their marginal edges, means for connecting adjacent flanges together and means for clamping all of said molding units together.
- 10 6. For concrete construction, a sheet metal mold unit adapted to form a recessed panel and provided with an aperture having a marginal edge provided with an off-set and 15 a separable pendant-decoration member ar-
- ranged in said aperture and provided with molding surfaces extending beyond the adjacent molding surfaces of said unit, said member attached to said unit at the edges of said aperture.
- 25 7. For concrete construction, a sheet metal mold unit adapted to form a recessed panel and provided with an aperture having a marginal edge provided with an off-set and a pendant decorative member arranged 30 in said aperture and having its marginal edge located in said off-set.
- In testimony that I claim the above, I have hereunto subscribed my name in the presence of two witnesses.

FRANK M. VOGAN.
